HAIR CURLER

Jacob Goodman, Brooklyn, N. Y., assignor to
Delamere Company, Inc., a corporation of Del-
aware

Application October 4, 1935, Serial No. 43,497

3 Claims. (Cl. 132—44)

This invention relates to a hair curler, and more particularly to a curler of the type having a cylindrical tubular body member around which the hair may be wound, and which is adapted 5 to be used either for curling the ends of a lock of hair, or for forming and supporting the hair in a roll, as well as for other purposes.

The various forms of curlers of this type now on the market or heretofore devised have embodied one or more relatively hard or rigid parts, such, for instance, as a metal tube, or a metal spring for clamping the hair ends. The use of any hard or rigid parts in the construction of the curler makes it uncomfortable to wear during sleep, or, if worn as a support for a hair roll during the day, results in giving the hair roll an unnatural, stiff appearance.

The primary object of my invention is to overcome these objections by the provision of a curler 20 which is made wholly of soft and pliable parts.

Another object is to provide a curler of this type having a resilient, tubular body upon which the hair may be wound into a curl or formed to 25 into a roll, and which may be easily applied to and removed from the ends of the hair.

A further object is to provide a curler having novel means for clamping the ends of the hair on the tubular member while the hair is being wound or rolled thereon.

30 A still further object is to provide a curler of this type with means for fastening it in place after the hair has been wound or formed into a roll.

An important feature of my improved hair curler is that its soft, non-rigid construction permits it to be kept in the hair over-night without the slightest discomfort to the wearer. Furthermore, its highly pliable construction enables it to be readily shaped to conform to the contour of the head so that in use as a support for a roll when the hair is dressed the roll will have a soft, natural appearance. In its use as a hair roll supporter, the hair may be draped around the ends of the curler, entirely concealing them, and rendering the curler invisible in the hair.

45 Other objects and advantages of the invention will appear from the following description thereof, reference being had to the accompanying drawing, in which:—

50 Figure 1 is a view in elevation, partly broken away, of a hair curler embodying the invention;

Fig. 2 is a plan view of the curler showing the pliable clamping member positioned to clamp the 55 ends of the hair prior to the rolling thereof;

Fig. 3 is a perspective view showing the hair clamped and partly rolled on the curler;

Fig. 4 is a similar view with the fastening means positioned to hold the curler in the hair after the hair has been wound thereon; and,

Fig. 5 is a sectional view of a modified form 5 of the curler.

The curler comprises a tubular cylindrical body member 10 made of soft rubber or other suitable non-rigid material, around which the lock of hair 10 is wound in forming a curl or roll. The hair is generally moistened with water or hair lotion before being curled. If desired, the wall of the tube may be provided with perforations 11 to facilitate drying.

15 12 indicates a hair ends clamping member made of pliable non-resilient covered wire, such as braided wire. This member has an inner portion or arm 13 extending into and fastened with in the bore of the tubular member 10, and an outer portion or arm 14, preferably in the form of a loop, which extends outward from one end of the tube and is adapted to be bent lengthwise over the tube, as shown in Fig. 2, to clamp the ends of the hair against the tube prior to winding or rolling the hair thereon. The member 20 25 25 12 is of such character that it may be easily bent but that when bent, it will maintain its bent form.

Extending outward from each end of the tube 30 10 is an arm 15 made of pliable non-resilient covered wire similar in character to the wire used for the clamping member 12, and preferably in the form of a loop, but shorter in length than the arm 14 of the clamping member. The 35 two arms 15 together function and operate to lock or fasten the curler in place when the hair has been rolled up, and therefore they may be called a locking member. The parts 12 and 15 may be made of a single length, or of separate 40 pieces, of covered wire, and they may be secured to the tube by a staple 16 or other suitable fastening means.

In use, the curler is brought into position under the ends of a lock of hair 17. The arm portion 45 14 of the clamping member 12 is then bent around over the tube, as shown in Fig. 2, and is pressed down to clamp the hair ends firmly on the tube. The tube is then rotated axially to wind the desired length of hair thereon. The winding is 50 generally continued until the hair is rolled close to the scalp. The arms 15 provide a convenient means for rotating the tube as they may be readily grasped between the thumb and forefinger of both hands of the operator. After the hair has 55

been wound on the tube, the arms 15 are bent over the roll of hair, as shown in Fig. 4, to lock the curler in place and prevent the hair from unwinding. The curler may be left temporarily in the hair until a curl has been set, or it may be worn in the hair as a support for the hair roll. The curler, with the hair wound thereon, may be easily bent to shape the roll to conform to the curvature of the head, and when so bent, the pliable clamping arm serves to maintain it in its bent form.

A modified form of the curler is shown in Fig. 5, wherein 20 indicates the soft tubular body member, and 22 the pliable covered wire member for clamping the ends of the hair. These parts are substantially similar in construction, and function in the same manner as the corresponding parts 10 and 12, respectively, of the form of curler previously described and illustrated in Figs. 1 to 4, inclusive, of the drawing. The modified curler is provided with a locking member 21 consisting of a rubber cord or band attached at one end, by a staple 23 or other fastener, to one end of the tube, and having a tip 24 at its free end. With this form of curler, after the hair has been wound on the tube, the locking member 21 is passed over the hair and its tip is inserted in the other end of the tube to lock the curler in place and preclude it from unrolling.

30 What I claim is:—

1. In a hair curler of the character described, the combination of a flexible tubular hair winding member upon which the hair may be wound, a pliable wire hair clamping member disposed within and projecting outward from the tubular member and adapted to be bent lengthwise against the

tubular member to clamp the ends of the hair thereon prior to winding and to retain its bent form, and a locking member comprising two pliable wire arms, one extending outwardly from each end of the tubular member and adapted to be bent towards each other across the hair wound on the tubular member to fasten the curler in place in the hair.

2. In a hair curler of the character described, the combination of a soft rubber tubular hair winding member upon which the hair may be wound, a hair clamping member of covered pliable wire secured to the tubular member and adapted to be bent lengthwise thereof to clamp the ends of the hair thereon prior to winding, and a locking member comprising two loops of covered pliable wire, one extending outwardly from each end of the tubular member and adapted to be bent towards each other across the hair wound on the tubular member to fasten the curler in place in the hair.

3. In a hair curler of the character described, the combination of a soft rubber tubular hair winding member upon which the hair may be wound, a hair clamping member comprising a loop of covered pliable wire secured to the tubular member and adapted to be bent lengthwise thereof to clamp the ends of the hair thereon prior to winding, and a locking member comprising two loops of covered pliable wire, one extending outwardly from each end of the tubular member and adapted to be bent towards each other across the hair wound on the tubular member to fasten the curler in place in the hair.

JACOB GOODMAN.
